UNITED STATES PATENT OFFICE

MARCEL DELAMARE DEBOUTTEVILLE, OF NEUILLY-SUR-SEINE, FRANCE

PROCESS OF WEAVING AND APPARATUS THEREFOR

Application filed August 12, 1930, Serial No. 474,807, and in France August 14, 1929.

My invention has for its object an improved process of weaving on dobby or Jacquard looms and apparatus facilitating the carrying out of the improved process.

5 In present methods of weaving the warp threads are passed through the eyes of successive shafts or hooks (according to whether dobby or Jacquard looms are used) in repeated succession or with reversal of order. 10 This is shown diagrammatically in Figure 1 of the accompanying drawings in which the horizontal lines 1, 2, 3, 4 represent four shafts and the vertical lines a^2 , b^2 , c^2 , d^2 , represent the warp threads passed through 15 the eyes of these shafts; the left hand part of the figure shows threading in repeated succession and the right hand part threading in succession with reversal of order.

According to my invention a pattern is 20 woven on a ground by a method in which the members of the loom (shafts of a dobby or hooks of a jacquard) causing the warp threads to move to form the shed are grouped into two or more "sections", one or more sections being moved as a whole at each pick 25 throughout the weave in a predetermined order to form the ground and one or more individual members being moved in addition where the pattern occurs, the succession of 30 combinations of shafts or hooks of the general "order" of sections and of shafts or hooks being so arranged that at least any two successive combinations have no shaft 35 or hook in common.

It will be understood that in general certain warp threads will be raised to form the shed but all that is stated in the description and the claims must be understood to be 40 equally applicable to a loom in which particular warp threads are lowered to form the shed.

In the following description, for the sake of simplicity, mention will only be made of the shafts of a dobby loom, but all that fol-

lows would apply equally well to a Jacquard loom.

According to a further feature of the invention improved mechanism is provided for carrying out this method of weaving. In 50 this mechanism the harness comprises two or more groups of shafts, each of which groups may be divided into sections as described above, and will be raised according to its own shedding diagram, and the eyes are each 55 connected by two or more heald cords to shafts in different groups in such a manner that whatever the complexity of the effective threading diagram, the actual threading diagram to the eyes follows a simple law such 60 as that for calico weave or twill.

Guiding grids are preferably provided for the cords so that the shafts and the eyes move in a substantially vertical direction.

In the method of weaving forming the subject of the present invention, the sections may vary as to the number of shafts they comprise. The different sections do not control constantly the warp threads of one and the same system, but at each pick a new grouping takes place, so that a section which controls threads for the ground, may control or influence, in the following raising, threads for the pattern.

Each of the successive warp threads is 75 passed to one of the shafts of one of these sections, the order in which the sections themselves and the individual shafts within each section succeed each other constitutes what 80 will be called the general "order" of the sections and of the shafts; this disposition will be described hereinafter. This passage of the warp threads to the shafts will be represented graphically by a broken or discontinuous line 85 of any complexity having this "order" as base.

To weave the ground of the material certain sections are raised alone or in groups and to weave the pattern which must show upon 90

the ground there are lifted at the same time one or more shafts of sections other than those which produce the ground according to a shedding line which also may be represented graphically by a broken line of any complexity and having this same "order" as base.

In the case in which the raising of one or more of the ground forming sections would produce interferences which would be destructive or injurious to the pattern care must be taken to raise all the shafts of that section or those sections with the exception of those which interfere with the pattern or conversely.

It is possible similarly in certain interesting cases to raise all the shafts of the sections intended to weave the ground, with the exception of certain shafts chosen systematically in accordance with the line of the design, for example the shafts which for each weft of the fabric for example the shafts which for each weft of the fabric precede and follow in the "order" of combinations the shaft or shafts of the design specified in the shedding diagram.

The accompanying drawings illustrate the invention.

In these drawings, Figure 1, which has already been referred to, shows customary methods of threading the warp.

Fig. 2 shows methods of warp threading according to the invention and sets out the division into "sections".

Figure 3 gives details by way of example of a weaving diagram and the fabric produced. A simple diagram has been chosen for the sake of clarity.

Figs. 3^a, 3^b, placed side by side, constitute a diagram which is an enlargement of Fig. 3 with added details. The line of division between 3^a and 3^b corresponds with the vertical line $x-x$, Fig. 3.

Figure 4 shows diagrammatically three different "orders" of sections and shafts.

Figure 5 shows diagrammatically improved harnesses for a dobby and Figure 6 is a detail.

In Figure 2 it has been assumed that the shafts are divided into three sections, section A comprising four shafts, section B six, and section C four.

Instead of passing the successive warp threads through one shaft after another as in Figure 1, they are passed through one section after another and in each section in a particular shaft (as indicated in the left hand part of Figure 2) adopting for example a diagram with reversal of order for the sections; a diagram with repeated succession could be just as well adopted in the sections as is shown in the right hand part of Figure 2. It will be seen that as represented at the left side of said figure the order is one of repeated reversal— a^2, b^2, c^2, b^2, a^2 , etc.—

whereas the order represented at the right is one of repeated succession— $a^2, b^2, c^2, a^2, b^2, c^2$, etc.

To determine the threading of the warp threads through the shafts, one proceeds by a graphical method as set forth in the following description and as represented by the irregular or broken line a, b, c, d , etc. in the upper left hand part of Figures 3^a, 3^b taken together which give a threading diagram.

Immediately at the right of said broken line a, b, c , etc., is a vertical column of numbers composed of three vertical lines of digits, the first line being headed by the letter "C", the next by "B", the next by "A" representing the three sections of the example under consideration. The figure "4" just above the letter C indicates that section C comprises 4 shafts; and the figures 6 above B and 4 above A have a like significance.

In this diagram the characters A1, B1, C1, etc., are not used both for lack of space and also to avoid complication. Instead the symbols "x" for section A, "o" for B and "+" for C are employed. Throughout the diagram, Figs. 3^a, 3^b, symbol "x" indicates the warp threads comprised in section A, o those of section B, and + those of section C.

It will be seen that the broken line a, b, c, d , etc. is formed by a succession of these symbols.

In said vertical column of numbers the figure "2", for example, in line one (that under C) signifies C2; figure 3 in line two signifies B3, etc.

Thus it will be understood that the numbers in the first line of the vertical column represent the shafts 1, 2, 3, 4 of section C; the numbers in the second vertical line represent the shafts 1, 2 . . . 6 of section B, and so on. In the following description, however, for the sake of simplicity, the shafts will be designated C1, C2, C3, etc., B1, B2, B3, etc. As will be seen by reading vertically down each of the three lines of the column, the shafts are repeated in each section in consecutive order: 1, 2, 3, 4 (line C); 1, 2, 3, 4, 5, 6 (line B), etc. It may therefore be said that the "order" of the shafts is consecutive. On the other hand, the order of the sections A, B, C is one of repeated reversal. This will be seen by reading the numbers consecutively in either direction as they follow a zig-zag course. Thus, from the bottom upward the sections occur in the order: C, B, A, B, C, etc.

As already stated, the irregular broken line $a, b, c, d, e . . .$ represents the threading diagram and shows the order of the warp threads to the shafts, which are supposed to have a vertical direction in respect to the plane of the figure (see arrows f1).

From what has been said above it will be understood that the said vertical column would read, if the characters A1, B1, C1, etc.,

were used instead of the corresponding symbols, as follows:

Any three consecutive sections from right to left, or vice versa (as A1, B1, C1, or C1, B2, A2) constitute a "combination".

30 The foregoing explanation of the vertical column of figures applies in general to the three-fold horizontal line of figures, which represent the shedding diagram, and which is referred to below.

35 If this diagram is examined, it will be seen that: warp thread No. 1, that is, the thread marked + at the very beginning of the pattern line *a*, *b*, *c*, etc., is passed to shaft 4 of section C, warp thread No. 2, the one next 40 above and to the right, is passed to shaft 3 of section B, warp thread No. 3 is passed to shaft 4 of section A, and so on.

45 Of course for the threading diagram any other line could be adopted than the line *a b c d e f*, etc., shown in the upper part of Figure 3 and corresponding to the design which it is desired to produce on the material. For a given "order" of sections and shafts an infinity of threading diagrams can be envisaged which will give with appropriate shedding diagrams families of different designs.

50 In the "order" of sections and shafts the succession of shafts of a complete group of consecutive sections is called "a combination". Thus in the example shown, the "order" of sections and shafts comprises (reading from the top of the column) the combinations A₁ B₁ C₁, C₁ B₂ A₂, A₂ B₃ C₂, etc.

55 Now if one considers for example the combination A₁ B₃ C₁ (the ninth from the top) it will be seen that it is necessary to go up as far as the combination A₂ B₃ C₂ (the third from the top) and down as far as the combination A₄ B₃ C₄ (the fifteenth) to find other 60 combinations having a shaft, B₃, common to

the combination in question. This distance which is measured by the number of shafts which separate the two successive repetitions of B₃ is what one may call the "absolute freedom", equal here to 12. It is in fact necessary that in every "order" of sections and shafts a given combination should have no shaft in common with at least the preceding and the following combination. This is the condition as will be seen later, for obtaining 75 purity in the lines of the pattern.

70 The lower right hand part of Figure 3 shows the shedding diagram, that is to say, the order in which the shafts of the sections must be raised to form the pattern which it is desired to obtain. This is repeated in Fig. 3^a, 3^b where it is represented by an irregular broken line *m*, *n*, *o*, *p*, composed of the same symbols as line *a*, *b*, *c*, *d*, etc.

75 The three-fold line or column of numbers, which extends across the sheet just above the middle line thereof, shows as before the "order" of sections and shafts but arranged horizontally instead of vertically.

80 The vertical "order" of passage to the shafts and the horizontal "order" of shedding correspond with each other in such a way that the horizontal line passing, for example, through a shaft A₁ of the passage to the shafts cuts the vertical line passing through A₁ of the shedding on an axis at 45° called "axis of multiplication" of the two diagrams; the secondary lines represented by the lines of the sections above and below this axis represent the "phantom characteristic" of the 85 "order" or the network of "interferences".

85 The broken line *m*, *n*, *o*, *p*, etc., represents the shedding diagram corresponding to the pattern it is desired to obtain. The arrow /2 indicates the direction of the weft threads. If this diagram is examined it will be seen that:—

90 The first opening of the warp making a shed for the first pick causes the shaft C₄ to rise, as indicated at + adjacent to the beginning, *m*, of the line. Directly above this symbol + will be found a figure 4 in the horizontal line C, thus indicating the shaft C₄.

95 The second opening of the warp making a shed for the second pick causes the shaft B₃ to rise, as indicated by symbol *o* and the number 3 directly above.

100 The third opening of the warp making a shed for the third pick causes the shaft A₄ to rise.

105 The fourth opening of the warp making a shed for the fourth pick causes the shaft B₂ to rise, and so on.

110 But at the same time as the pattern, it is necessary to weave the ground of the fabric and this ground must be so chosen as to avoid too great floats of weft and warp or at least floats not greater than those considered to be admissible.

To weave the ground the sections are raised in accordance with a cyclic law depending solely on the ground chosen in accordance with the possibilities of the "order".

- 5 If in the case considered (that is to say in the case of the three sections A B C) the three sections A B C are raised consecutively with reversal of order (which is the order in which warp threads are passed successively 10 and alternately to the three sections) a three shaft cross twill will be produced; if on the contrary the sections A and C are raised together alternating with B alone, a ground of calico weave will be produced.
- 15 In the example considered a calico weave ground has been chosen and it has been necessary to determine the sections required to make the ground according to the general pattern it is desired to obtain on the fabric.
- 20 If for a calico weave there are raised for example in alternation sections A and C together (to the shafts of which all the odd warp threads pass) and section B alone (to the shafts of which all the even warp threads 25 pass) it will be seen that the shaft C₄ which already rises to make a shed for the first pick of the pattern also rises with the group A C for the ground, and that thus no pattern will appear in this part of the fabric. For the 30 second pick of the pattern it is necessary to raise, as seen above, the shaft B₃, but if at the same time all the shafts of section B rise for the ground, there again the pattern will be swallowed up by the ground and nothing 35 will appear.

It is therefore necessary so to choose the sections or groups of sections to raise for the ground as not to destroy or injure the pattern. The shafts operating for the pattern 40 must for this purpose never be the same as those operating for the ground or interlacing.

In the case considered it is possible to determine as follows the sections or groups of sections to raise for interlacing at the same 45 time as the pattern:

With the shaft C₄ for the pattern section B will be raised for interlacing,

With the shaft B₃ for the pattern sections A and C will be raised for interlacing,

50 With the shaft A₄ for the pattern section B will be raised for interlacing,

With the shaft B₂ for the pattern sections A and C will be raised for interlacing, and so on for successive picks.

55 There is thus obtained a calico weave ground on which the design will show very clearly and which not only will not destroy the pattern but will also strengthen it by trebling the line proper of the pattern as can be seen by examining the lower left hand part of Figure 3 which shows the fabric obtained with its pattern. It will be seen that to the thread for the pattern C₂, above referred to, are joined in combination, because 60 of the ground, the two warp threads B₂ and

A₄—and so on for all the other threads for the pattern so that the line of the pattern is trebled by the ground. This pattern is obtained by "multiplication" of the threading diagram by the shedding diagram. As before, there are shown by "o", by "+" and by "x" the warp threads passing to the shafts of sections B, C and A respectively. Further, the calico weave ground of the fabric is shown by dots in a part of the figure.

If the part of Figure 3^b near the letters *a m* is examined it will be seen that the first shedding causes the shaft C₄ to rise for the pattern and all the shafts of section B for the ground or interlacing; this shedding produces by the picking of the first weft the first horizontal line of the pattern D.

The second shedding causes the shaft B₃ to rise for the pattern and all the shafts of sections A and C for interlacing; it produces by the picking of the second weft the second horizontal line of the pattern D.

The third shedding causes the shaft A₄ to rise for the pattern and all the shafts of section B for interlacing. It produces by the picking of the third weft the third horizontal line of the pattern D, and so on.

The shafts C₄ B₃ A₄, etc., give by being successively raised the principal pattern which is shown surrounded by a thick continuous black line. This "principal pattern" further results automatically from the multiplication in a kind of geometrical way of the broken lines *a b c* etc., *m n o*, etc., of the threading and shedding diagrams. The raising of these shafts also produces a "secondary pattern" shown by "+"s", "o's" and "x's" from place to place on each of the horizontal lines representing successive picks; this secondary pattern, which remains soft because discontinuous, results from the raising of warp threads belonging to other elements of the line *a b c d*, etc., of the threading diagram than those which correspond to the element considered of the line *m, n, o, p*, etc., of the shedding diagram.

If the basic "order" of the sections and shafts has been suitably chosen this secondary pattern will be in perfect harmony with the principal pattern and this is one of the fundamental and indispensable reasons for the existence of these harmonic dispositions.

The raising of the shafts of section B, then of sections A and C, then of section B, then of sections A and C, etc., will give the calico weave ground shown by the dots near the centre of Figure 3.

In order to have a clear separation of the principal and the secondary pattern, the shafts must be arranged in each section in such a way that a determined "combination"—i. e. the succession of the shafts of a complete range of all successive sections in contemplation—have no common shaft and more generally that a given combination be as far

as possible from the combination having with it one or several common shafts.

The above example has only been given by way of a non-limiting example; of course by 5 adopting a different "order" and different lines for threading and shedding diagrams a practically limitless variety of patterns would be obtained.

Figure 4 shows three other examples out 10 of the many possible "orders". The first (on the left) shows four sections comprising respectively 4, 6, 4 and 6 shafts with "order" of sections in succession and shafts in succession. The second shows three sections 15 comprising 4, 7 and 4 shafts respectively with "order" of sections in order with reversal and shafts in succession. The third shows three sections comprising 4, 7 and 4 shafts respectively with "order" of sections in order 20 with reversal and shafts in order with reversal. The most general "order" have any desired number of shafts or hooks per section, but the "order" of the sections is usually in succession or in order with reversal and 25 the "order" of the shafts in each section is also usually in succession or in order with reversal.

As has been said before one may call "combination" a group of shafts each of which 30 belongs to different sections taken consecutively. For example in the first "order" of Figure 4 the successive combinations are: A₁ B₁ C₁ D₁, A₂ B₂ C₂ D₂, etc.

It will be noted that in this "order" the 35 initial combination A₁ B₁ C₁ D₁ is found again after $12 \times 4 = 48$ shafts; 48 is what may be called the "relative freedom" or the field of relative freedom.

The "absolute freedom" is measured as explained 40 previously by the number of shafts separating two successive repetitions of the same shaft in the shortest section; in the particular case just referred to from A₁ of the combination A₁ B₁ C₁ D₁ to A₁ of the combination A₁ B₅ C₁ D₅ there is a separation 45 of 15 shafts and A is the shortest section (A = C = 4 shafts); 15 is thus the measure of the absolute freedom for this "order".

As has been indicated at the beginning this 50 new process is applicable not only to looms working with a dobby, but also to looms working with jacquard mechanism.

Figure 5 of the accompanying drawings shows a special type of harness particularly 55 suitable for carrying out on a dobby loom the process forming the subject of the present invention.

This harness is made up of any suitable 60 number of shafts *a*, which are the ordinary shafts of a dobby loom, and their function is to raise the warp threads which pass through the hole *f* of member *e*.

These shafts each support by means of 65 hooks a metallic rod *b*⁴ of rectangular section on which are hooked cords similar to

those of the harness of the jacquard mechanism.

These groups are each made up of an upper double thread *c*⁴ attached to the upper hole *d*² of an eye *e*, which has a hole *f* through 70 it for the passage of the warp thread (Figure 6). The double thread *c*⁴ is hooked at its upper part to the rods *b*⁴ of two different shafts *a*⁴. To the lower hole *d'* of the eye *e* is attached the end of a thread *g* which forms 75 the lower part of the cord and on which is hung in the known way a lingo *h*.

The shafts *a*⁴ may be divided for example into two groups I and II, each of the double cords *c* ending then at its upper part in one 80 shaft of the group I, and in one shaft of the group II.

At their upper part the shafts *a*⁴ are connected in the usual way to the hooks of the 85 dobby.

The metallic rods *b*⁴ of the shafts *a*⁴ rest on the cross pieces *i* of a fixed grid made up of a certain number of strips of wood *j* in which are drilled holes *i*, the distance between which is equal to the division of the 90 dobby. Into these holes *j* are put rods of brass. The grid thus formed has the purpose of ensuring the accurate vertical displacement of the shafts *a*.

Below the eyes *e* of the cords there is a 95 second grid or lower grid made of cross pieces *k* in which are drilled holes *l* in which are set for example rods of brass. This grid only comprises a small number of divisions, four or six for example, and its purpose is 100 to make it possible to reduce the width of the harness at the height of the warp and to ensure a suitable and systematic sub-division of the lingoes *h*. By means of this arrangement the width of the harness may for example be only eight to twelve centimetres and 105 is independent of the number of shafts of the loom.

The warp threads such as *I* may be just 110 passed through the eyes *e* of the cords, in consecutive order for example, corresponding to the sub-division of the eyes and consequently of the lingoes *h*, the order of passage of warp threads to the eyes having the purpose only of dividing and stepping the lingoes uniformly.

On the other hand, the effective threading to the shafts according to the more or less complicated threading diagram which may be adopted (for example a diagram such as that shown in Figure 3) will be replaced by a suitable hooking of the cords to the shafts controlled by the hooks of the dobby.

If then in the course of weaving several 125 consecutive threads break the weaver has not to take into consideration for connecting them up again the effective passage of warp threads to the shafts (more or less complex) but only the simple order adopted for the passage of the warp threads to the eyes *e*.

The double cords *c* from each eye are attached both to a shaft of group I and to a shaft of group II so that one warp thread can be controlled at the same time by two different shafts.

The shafts may of course be divided into more than two groups and in that case there will generally be as many divisions of the cord from each eye as there are groups of shafts, and thus one warp thread can be controlled by as many different shafts as there are groups.

It is possible thus to carry out for example by means of group I a threading corresponding to a particular pattern to be worked and to carry out for this pattern interlacing or the general ground of the fabric by means of group II.

It is also possible to combine in groups I and II methods of threading corresponding to two different patterns intended to be complementary to each other, each group of shafts participating in the interlacing or general ground by means of the sections of which it is made up.

As will be seen it is possible with harness of this kind comprising any desired grouping of shafts to utilize a very large number of combinations making it possible to produce any pattern and any ground desired with the greatest facility of execution in accordance with the process forming the subject of the present invention.

It will be understood from what has been already stated that, for the purposes of this invention, the shafts of a dobby loom and the hooks of a Jacquard loom are the equivalents of each other. Hence where a "shaft" is specified in the appended claims, it is to be clearly understood as signifying either the shaft of a dobby loom or the hook of a Jacquard loom:

What I claim is:

1. A harness for realizing the process herein described comprising several groups of shafts and in which the eyes for the warp threads are controlled through the intermediary of a double cord, by two different shafts controlled themselves by the hooks of the loom, the shafts and the hooks being thus divided into two groups working simultaneously or alternatively.

2. Harness as claimed in claim 1, comprising two guiding grids, one upper grid for the cords below the shafts and having the same division as the hooks of the loom and one lower grid for the lingo cords and having a small division.

3. Harness as claimed in claim 1, in which the warp threads are passed into the eyes—for instance in repeated succession—the threading to the shafts according to the threading diagram being replaced by a suitable hooking of the cord to the shafts controlled by the hooks of the loom.

4. Process of obtaining on suitable looms fabrics having patterns of new type, characterized by grouping or "ordering" the shafts in groups or "sections" which follow each other in regular order (repeated succession or repeated reversal); each of said sections comprising a plurality of shafts also following each other in a predetermined order (repeated succession or repeated reversal); establishing with such an "order" as a base the shedding and threading diagrams; raising according to the shedding diagram the shafts which produce the pattern; and simultaneously raising to form the ground of the fabric all the shafts of one or several "sections", according to the ground to be obtained.

5. In the process of obtaining on a suitable loom fabrics having patterns of new types, characterized by grouping or "ordering" the shafts in "sections" for repeated use, either in the same or reverse order, the step which consists in raising a certain section or group to form the ground of the fabric and simultaneously raising, to produce the pattern, one or more individual shafts belonging to sections other than those raised to produce the ground.

6. Process of obtaining on suitable looms fabrics having patterns of new types, characterized by grouping or "ordering" the shafts in groups or "sections" which follow each other in regular order (repeated succession or repeated reversal); each of said sections comprising a plurality of shafts also following each other in regular order; establishing with such an "order" as a base the shedding and threading diagrams; raising according to the shedding diagram the shafts which produce the design; and raising alternately after each weft of the design all the shafts of one or several sections to form the ground of the fabric.

7. Process of obtaining on suitable looms fabrics having patterns of new types characterized in that the shafts, instead of being actuated individually, are divided into groups or "sections" each composed of a different number of shafts from that of at least one of the other sections; which sections follow each other regularly in a determined order such as repeated succession or repeated reversal; the shafts in each section also following each other in a determined order, such as repeated succession or repeated reversal.

8. Process of obtaining on suitable looms fabrics having patterns of new types characterized in that the shafts, instead of being actuated individually, are divided into groups or "sections" each composed of the same number of shafts; which sections follow each other regularly in a determined order such as repeated succession or repeated reversal; the shafts in each section also following each other in a determined order, such as repeated succession or repeated reversal.

9. Process of obtaining on suitable looms fabrics having patterns of new types according to claim 4, characterized in that the shedding and threading diagrams established on the basis of the "order" of the "sections", and the "order" of the shafts in each section are constituted by continuous lines respecting the "order" of the sections.

10. Process of obtaining on suitable looms fabrics having patterns of new types according to claim 4, characterized in that the design is realized by raising successively the shafts indicated by the shedding diagram, and that the ground of the fabric is realized by raising simultaneously all the shafts constituting one or several sections other than those operated for the design.

11. Process of obtaining on suitable looms fabrics having patterns of new types according to claim 4, characterized in that the design is realized by raising successively the shafts indicated by the shedding diagram, and that the ground of the fabric is realized by raising, alternately after each weft of the design the shafts constituting one or several sections.

12. Process of obtaining on suitable looms fabrics having patterns of new types according to claim 4, characterized in that the generative continuous lines (axis of multiplication) and therefore the generative continuous lines or threading diagram ($a b c d \dots$) and shedding diagram ($m n o p \dots$), which lines determine the "principal design" to be realized, simultaneously determine in the "order" field a net of secondary discontinuous lines, which produce a "secondary design" weaker than the said principal design and which completes and harmoniously accompanies the same and distinguishes the fabrics made according to the method claimed from those obtained by the usual methods.

In testimony whereof I have signed this specification.

MARCEL DELAMARE DEBOUTTEVILLE.
